(57) CLAIM

The ornamental design for a tote bag, as shown and described.

DESCRIPTION

FIG. 1 is a perspective view for a tote bag showing our new design;

FIG. 2 is a front view thereof;

FIG. 3 is a rear view thereof;

FIG. 4 is a first side view thereof;

FIG. 5 is a second side view thereof; and,

FIG. 6 is a top plan view.

The broken lines immediately adjacent to the shaded area represent unclaimed boundaries of the design. The broken lines showing the remainder of the bag are for environmental purposes only and form no part of the claimed design. The shading on the straps represents a terry cloth appearance. The shading shown on the top portion of the tote bag represents a material having an appearance contrasting the terry cloth strap.
